(57) **CLAIM**

The ornamental design for a electric can opener, as shown and described.

DESCRIPTION

FIG. 1 is a perspective view of a electric can opener showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and

FIG. 8 is a bottom plan view thereof; and

FIG. 9 is a partial enlarged view of portion 9 in FIG. 2. The dash-dot-dash line is included for the purpose of illustrating the bounds of the enlarged view and forms no part of the claimed design.

The broken lines depict portions of the electric can opener and form no part of the claimed design.

1 Claim, 9 Drawing Sheets
